[57] CLAIM

The ornamental design for a luggage roller, as shown and described.

DESCRIPTION

FIG. 1 is a bottom plan view of a first embodiment of a luggage roller showing my new design;

FIG. 2 is a side elevational view thereof; the side opposite being a mirror image;

FIG. 3 is a front elevational view thereof;

FIG. 4 is a top plan view thereof;

FIG. 5 is a bottom plan view of a second embodiment of the luggage roller showing my new design;

FIG. 6 is a side elevational view thereof;

FIG. 7 is a front elevational view thereof; and,

FIG. 8 is a top plan view thereof.

FIG. 1

FIG. 3

FIG. 4

FIG. 2

FIG. 8

FIG. 7

FIG. 5

FIG. 6
